UNITED STATES PATENT OFFICE

JAY W. SMITH, OF ALGONAC, MICHIGAN

DESIGN FOR A RUNABOUT BOAT

Application filed June 18, 1927. Serial No. 22,490. Term of patent 14 years.

To all whom it may concern:

Be it known that I, JAY W. SMITH, a citizen of the United States, residing at Algonac, in the county of St. Clair and State of Michigan, have invented a new, original, and ornamental Design for a Runabout Boat, of which the following is a specification, reference being had to the accompanying drawing, forming part thereof.

Fig. 1 is a bottom plan view;

Fig. 2 is a side elevation of a runabout boat, showing my new design;

Fig. 3 is a front elevation, looking at the bow; and

Fig. 4 is a rear elevation, looking at the stern.

I claim:—

The ornamental design for a runabout boat, as shown.

JAY W. SMITH.
